[57] CLAIM

The ornamental design for a combined belt and tennis ball pouch, substantially as shown and described.

DESCRIPTION

FIG. 1 is a front perspective view of a tennis ball pouch showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and
FIG. 8 is a front perspective view thereof in which the pouch is illustrated in an expanded condition as if tennis balls were contained therein.
The belt is shown in a looped configuration throughout the views for convenience of illustration only.
